(57) **CLAIM**

The ornamental design for a combined phone mount with cup holder, as shown and described.

DESCRIPTION

FIG. 1 is a front and top perspective view of a combined phone mount with cup holder, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of a portion indicated with numeric 9 in FIG. 1; and,

FIG. 10 is an enlarged view of a portion indicated with numeric 2 in FIG. 10.

The broken lines in the figures illustrate portions of the combined phone mount with cup holder that form no part of the claimed design. The dash dot dash lines in FIGS. 1, 2, 9 and 10 are for the purpose of depicting the boundary lines of the enlarged views and form no part of the claimed design.
